United States Patent

Des. 238,278
Patented Dec. 30, 1975

238,278

HOUSING FOR WINDOW AIR CONDITIONER

Walter Baker, Jr., Louisville, Ky., assignor to
General Electric Company

Filed July 19, 1974, Ser. No. 490,417

Term of patent 14 years

Int. Cl. D23—04

U.S. Cl. D23—144

FIG. 1 is a front elevational view of a housing for window air conditioner showing my new design.

FIG. 2 is an enlarged rear perspective view; the bottom and side not shown are mirror images of the top and side which are illustrated.

I claim:

The ornamental design for a housing for window air conditioner, as shown and described.
